Mark D. O'Donnell

UNITED STATES PATENT OFFICE.

ANNA D. ROSTOW, OF SUMMIT, NEW JERSEY.

NOSE-SHAPER AND SURGICAL SUPPORTER.

1,372,089.

Specification of Letters Patent. Patented Mar. 22, 1921.

Application filed February 21, 1920. Serial No. 360,523.

To all whom it may concern:

Be it known that I, ANNA D. Rostow, a citizen of the United States of America, residing at Summit, in the county of Union and State of New Jersey, have invented certain new and useful Improvements in Nose-Shapers and Surgical Supporters, of which the following is a specification.

The present invention relates to devices for shaping noses, and has for its principal object, to provide an improvement of the device described and shown in my U. S. Patent #1,100,991 of June 23, 1914, with the view of rendering the device more effective and of simplifying its construction and reducing its cost of manufacture.

With this and other objects in view, my invention consists in the novel construction, combination and arrangement of parts as will be hereinafter fully described and defined in the appended claims.

In the accompanying drawing which forms part of this specification and in which similar reference characters denote corresponding parts, Figures 1 and 2 illustrate the use of the device in a front and rear view; Fig. 3 is a central section of my device, designed for long or drooping noses; Fig. 4 is a perspective view thereof; Fig. 5 is a perspective view of a modified form of construction designed for broad, flat and broken noses; Fig. 6 is a cross section thereof; Fig. 7 shows the modified device in use, and Fig. 8 is a perspective view of a further modification.

Referring to the drawing more in detail, and first to the construction illustrated in Figs. 1-4 inclusive, 1 denotes the frame or form made of porous light weight material cut out substantially as the form of my device described and shown in my earlier patent to conform with the shape of normally built noses in all sizes. The device now under consideration is designed to be used for re-shaping abnormally long bumpy and drooping noses, and for supporting injured ones. With deformities of such character, it is necessary to raise the cartilage and exert a continuous gentle pressure on the fleshy parts of the nose thereby filling up the hollows at the base or sides of the nose generally present in such cases, and obtaining the results of a normally shaped nose. To be effective the device must be of correct size and normal shape and held in

proper position and with due pressure on the superfluous parts during the treatment. To this end I provide on the sides of the form 1 along its longitudinal edges, pads or cushions 2 each fixed at its ends by stitching or otherwise to the body 1. These pads are preferably made of tubular pieces of fabric having a filling of suitable soft material. Passed transversely over the body 1 and through the crevices 2' formed between the pads 2 and the body 1, is a band 3, (Fig. 4). The parts of the band extending outwardly through the slots or crevices 2' are folded in opposite directions so as to extend over and bear on the pads 2 and around the face and tied at the back of the head, as shown in Fig. 2. The pads 2 are made of such a thickness that they will project from the sides of the nose beyond the cheek-bones. The same serve a double purpose, namely, first to exert a gentle pressure against the sides of the broad nose when the band 3 is drawn taut and secondly to hold the parts of the band extending over the cheek bones evenly raised so as to prevent undue pressure on the cheek bones.

The tongue-shaped part 5 of the body 1, which is adapted to extend over and rest against the cartilage, is held with pressure against the latter by a band or tape 6, which is capable of being attached to the body 1 and the tongue 5, and is provided with suitable adjustment means which permit adjustment according to different sizes and will hold the shaper in proper position. This tape is adapted to be passed around the face and tied at the back of the head, as shown in Fig. 2.

A series of snap members 7, eyelets or the like, may be provided on each side of the portion of the band 6 which extends over the tongue 5 and counterparts 7' on the body 1, to allow the band 6 of being adjustably fastened to the body 1 in order to render it possible to remove the tape for cleansing the nose, sterilizing the shaper, adjusting the tape or band according to the pressure desired or the size of the nose to be treated and securing complete comfort until the wearer is accustomed to the necessary pressure on the nose.

The device being usually worn during the night or while the patient is lying down I provide a tape or band 8 mainly to hold the tongue 5 raised to bear with sufficient pres- 110

sure against the cartilage. The band 8 is adapted to be suitably fixed to the body 1 to extend centrally over the forehead and the back of the head. This tape is parted longitudinally at its free end to form two strips 8', 8² adapted to be folded over the top part of the head in opposite direction and to be tied together as at 9 (Fig. 1).

In applying the device, the central tape 8 is first folded over the head and passed to the back. Next the tape 6 and then the tape 3 are folded over the rear end of the tape 8 and tied in back, as described. Thereupon, the strips 8', and 8² of the tape 8 are folded over the tapes 3 and 5 and tied together as shown in Fig. 1.

On drawing the tape 8 taut the tongue 5 will be raised to press against the cartilage, raising the latter into the desired shape.

20 By the crossing over and tightening of the band 3 the pads 2 will be caused to exert a gentle pressure against the sides of the nose thereby building up the broad flat nose in the height and preventing the nose from spreading sidewise.

For noses known as flat or broad noses a somewhat different treatment is used, as the same require a pressure along the entire face of each side of the nose.

30 To this end a plate shaped member 10 of more rigid material than the body 1, preferably celluloid or the like, is attached to the flexible body to extend over a comparatively large area of each side of the body 1.

35 The tape 11 when crossed over the pads 2, as shown in Fig. 7, will cause the members 10 to support a fracture and to press against the sides of the nose. By a continued performance of such treatment the nose will be 40 restored to normal shape. If the abnormality be due to a fracture which normally results in crooked, flat or humped lines, such lines by the use of my mold, will soon be restored to normal shape. For holding 45 this device in position bands 11' and 12, similar to bands 6 and 8, may be used.

In Fig. 8 the body or frame 13 is made of a perforated piece of celluloid recessed at 14, 15, 16 and 17 to allow the passage and 50 attachment of the tapes 18, 19 and 20, corresponding to tapes 3, 6 and 8 in the first described construction.

What I claim and desire to secure by Letters Patent is:

55 1. A nose shaper comprising a body portion conforming in shape with that of a normal nose, flexible means adapted to fold around the face of the wearer and to serve to hold said body portion tightly in position and cushioning means for holding said flexible means raised from the cheek bones to prevent undue pressure on the latter.

60 2. A nose shaper comprising a body portion of flexible material, pressure members 65 of more rigid material than said body por-

tion extending over the sides of said body portion and stationarily fixed thereto, means for holding said body portion tightly in operative position; and cushioning means for holding said last named means raised from 70 the cheek bones of the wearer.

3. A nose shaper comprising a body portion having a cartilage member, pressure members fixed to said body portion, cushioning means on said pressure members, flexible 75 means adapted to be folded over said cushioning means for applying pressure to said pressure members, and for holding said body portion against lateral displacement, flexible means for holding said cartilage member 80 tightly against the cartilage portion of the nose and flexible means for holding said body portion against longitudinal displacement from its operative position.

4. A nose shaper comprising a body portion conforming in shape with that of a normal nose, pressure pads extending longitudinally over the sides of said body portion and flexible means extending transversely over said body portion and adapted 90 to be tied at the back to apply pressure to said pressure pads, the latter being adapted to hold said means raised from the cheek bones to prevent undue pressure on the latter.

5. A nose shaper comprising a body portion conforming in shape with that of a normal nose, pressure pads of soft material extending longitudinally over and being fixed at their ends to the sides of said body portion and flexible means extending transversely over said body portion and adapted to be passed between the latter and said pressure pads and then crossed over the latter to apply pressure to said pads, said pads 105 being adapted to hold said means raised from the cheek bones to prevent undue pressure on the latter.

6. A nose shaper comprising a body portion conforming in shape with that of a 110 normal nose, pressure members extending longitudinally over the sides of said body portion and consisting of tubular members, and flexible means extending transversely over the body portion and adapted to apply 115 pressure to said pressure members.

7. A nose shaper and surgical supporter, comprising a body portion conforming in shape with that of a normal nose and having a member adapted to extend over the 120 cartilage of the nose, and to support the cartilage against drooping, pressure members extending over the sides of the said frame and serving to exert pressure on the sides of the nose, a tape or band extending 125 transversely over said frame and between the latter and said pressure members and serving to press the latter against the said frame, said tape or band being raised by the said members to prevent undue pressure on 130

the face of the wearer, a tape or band adjustably attached to said frame to extend over said cartilage member to press the latter against the cartilage of the nose and 5 keeping said cartilage raised and means for supporting the frame in position on the nose.

8. A nose shaper and surgical supporter, comprising a body portion or frame of 10 fabric cut out and stiffened at its edges to conform in shape with that of a normal nose, plate shaped members of comparatively stiff material extending over the sides of said body portion and adapted to exert

pressure on the sides of the nose, a tape or band extending transversely over said frame and serving to press said members against the latter, pads or cushions along the outer edges of said members serving to hold said tape raised to prevent undue pressure on the 20 face of the wearer and means for supporting said body portion or frame in position.

In testimony whereof I affix my signature in presence of two witnesses.

ANNA D. ROSTOW.
